[57] CLAIM

The ornamental design for a livestock treatment gun, substantially as shown and described.

DESCRIPTION

FIG. 1 is a perspective view of the livestock treatment gun showing my new design;

FIG. 2 is a left side elevational view wherein the right side view is a mirror image thereof;

FIG. 3 is a front view thereof;

FIG. 4 is a rear view thereof;

FIG. 5 is a bottom plan view thereof; and

FIG. 6 is a top plan view thereof.
